COPYING MACHINE

Reinhart W. Pittman, Jackson Heights, N. Y., assignor to The Beck Duplicator Company, a corporation of New York

Application October 22, 1937, Serial No. 170,363

26 Claims. (Cl. 101—132.5)

This invention relates to copying machines, and more particularly to that type of machines known in the trade as spirit machines, wherein a master letter or the like is printed or typed, or otherwise prepared, with a suitable hectographic ink or carbon, on the reverse side of the master, which is in the negative form, and with this side turned outward of the drum to which it is attached, copies are produced that are given a surface moistening on the side of the sheet which contacts with the master under a suitable pressure roller to take off some of the ink from the master.

The primary object of the present invention, is to provide a simple, reliable, and efficient working machine, easy to handle and adjust to its best working conditions, operated either by hand or automatically, adapted with the present improvements for producing a higher grade of work, and a greater number of copies from one master, than is usually obtained on the present type of machines.

Other objects herein obtained, are by the use of improved adjusting devices of the machine, such as the impression roller co-acting with the drum, to make a quick adjustment from a greater or less contact between the master sheet and the copy, providing by this means a greater number of copies obtained from one master sheet, and maintaining a uniform shade or color of the imprint taken from the master. The amount of moisture delivered to the copy sheet to be copied, may likewise be instantly changed from a heavy to a light coating, or reversely, that is delivered by a feed roller, the lower one of a pair, that feeds and applies the moisture to the copy sheet, and a contact roller above the moistening roller acting as a companion feed roller with the moistening roller to propel the sheets to the drum, is regulated to be quickly changed to varying contact pressures.

Another object is the provision of means to obtain a perfect register with one another of the sheets to be copied, with respect to the position of the master fixed to the drum, which includes a master clamping member, so located in a cutout portion of the drum that one wall thereof becomes a part of the registering means.

A still further object, is to provide means to rotate the feed rollers continuously, or intermittently, these being the aforesaid moistening roller, and the contact feed roller co-operating therewith, for propelling the moistened sheets to the register stop position of the drum. When feeding the machine automatically, the rollers may

be continuously driven, or intermittently if desired, since an automatic feed member at the proper time, and adjustable for the purpose, forces the sheets to be copied between the revolving or stopped feed rollers, to reach the stop of the drum, while the drum is at rest and about to revolve again, or during the continuous rotation thereof. When feeding by hand, the feed rollers are intermittently stopped, to provide time to insert the sheet into the bite of the rollers, which start to rotate again at the proper time of rotation to propel the sheet to reach the stop of the drum, in the same manner as does the continuous feeding action of these feed rollers.

A still further object is to provide a container to hold a suitable supply of the moistening fluid, which container is so constructed to be a removable unit, carrying the aforesaid moistening roller, and its companion feed roller, together with other mechanism, to deliver and regulate the moisture applied to the copies. One form of this mechanism for applying the moisture to the feed roller, provides a shallow basin, in the top of the container, conforming to the lower portion of the moistening roller in which the same revolves, to be constantly supplied with the moisture, by a pumping system in the container to supply the basin from the main supply of the container, and maintain a uniform level thereof in the basin by an overflow from the basin to the main supply of the container, and a regulating roller, to regulate the amount of moisture taken from the basin, and delivered at the top of the exposed portion of the moistening roller to transfer the same to the sheets to be copied, and in another form thereof, the basin and the pump are omitted, and instead, an endless belt is suspended in the liquid, to the bottom of the container, and driven by a roller over which it is supported and held against the moistening roller which drives the belt, and thus supplies the liquid to the same.

A still further object is to provide a universal feed table, or work holder, arranged to feed the sheets therefrom automatically, or by hand. When feeding automatically, the top sheet of the pile of blanks is maintained at a uniform top position, to be engaged by a feed member, to move the sheets into the feed rollers, while these rollers are constantly or intermittently driven, as may be desired, and when feeding the blanks by hand, the rollers are preferably intermittently driven, and this top position of the blanks is not required, and the means for so supporting the

blanks, as well as the feed member, may be moved to an inactive position.

Other objects of my invention will be set forth in the following description and drawings, which illustrate certain preferred embodiments thereof, or will be obvious therefrom without being specifically pointed out. It will be understood that the foregoing general statement of the objects is intended merely to generally explain the same, 10 and not to limit it in any manner.

With the above and other objects of the invention in view, the invention consists in the novel construction, arrangement and combination of various devices, elements and parts, as set forth 15 in the claims hereof, certain embodiments of the same being illustrated in the said drawings and described in this specification.

In the accompanying drawings.

Fig. 1 is a plan view of my improved copying 20 machine, certain parts thereof being broken away to more clearly show the working parts.

Fig. 2 is a portion of the machine, in plan, parts in section, to show how the gearing is arranged.

Fig. 3 is a side elevation of the machine, as 25 seen from the left in Fig. 1, showing the feed table, and the automatic feed member in its operative position.

Fig. 4 is a sectional view of the machine, taken 30 on line 4—4 of Fig. 1, as seen from the left, indicated by arrows.

Fig. 5 is a perspective view of the liquid container, shown as a removable unit, embodying the feed rollers, the regulating roller, the basin in 35 which the moistening roller revolves, and the pump to supply the basin, from the main supply of the container.

Fig. 6 is an end elevation of the container unit, 40 as seen from the right of Fig. 5.

Fig. 7 is a plan view of one end of the container, partly in section, to show the construction.

Fig. 8 is a perspective view of the work holding 45 table, showing the means for elevating the blanks to maintain a uniform level of the uppermost sheet of the pile of blanks.

Fig. 9 is a side elevation of a portion of the machine, showing the means for quickly changing the feed rollers from constant to intermittent 50 rotation.

Fig. 10 is a longitudinal section of the drum, to show how the same is constructed and mounted.

Fig. 11 is a longitudinal section of the moistening and feed roller.

Fig. 12 is a modification of the means for supplying the liquid to the moistening roller, from the main supply carried in the container.

Fig. 13 is a modification showing in a diagrammatical manner, my improvements as applied to 60 a machine in which the drum is continuously driven, together with continuous rotation of the feed and moistening roller, and automatic feeding of the blanks.

Fig. 14 is a modification, similar to Fig. 13, and 65 shows the feed and moistening roller intermittently driven.

Figs. 15 and 16 are modified forms of the means for regulating the moisture.

As shown in the drawings, I provide, as is the 70 general practice in this type of machines, a pair of side frames, 2 and 3, held in spaced relation by tie bars, 4 and 5, with one side frame on the inner side thereof, provided with a train of gears, including a pinion 6 driven by a crank 7 from the 75 outside of the frame, for hand operation of the

machine, the pinion meshing with a gear 8, loosely mounted on a stud, to which gear, a gear 9, is attached having an interrupted part of its teeth arranged to engage a gear 10, having an interrupted portion, which gear is fixed to the drum of the machine, to provide intermittent rotation of the drum. The ratio of the gears as here shown, provides for four turns of the crank 7, to rotate the drum one complete rotation, and during one rotation of the crank the drum is at 10 rest, due to the interrupted portion of the gears. With my improvements the drum could be continuously operated, I will first describe my invention, however, in connection with the interrupted action of the drum. The drum indicated at D, is 15 loosely mounted to rotate on a shaft 12, fixed against rotation to the side frame 2, by a nut and washer, as at 13, the gear 10 being adjustably fixed to the drum.

The drum D, a cylindrical structure, has end walls 14 and 15, with central openings for the reception therein of hubs, 16 and 17, fixed to the walls by screws, at the end 14, the hub 16, has the gear 10, with a sleeve-like hub 10' mounted on the hub 16, at one end of the sleeve an arm 25 10'' keyed to the sleeve of the gear, which arm has an arcuate slot 14' through which a binding screw 14'', threaded into the side wall 14, holds the gear in any desired adjusted position, to enable the adjustment of the drum with respect to a 30 master clamping bar 18 carried by the drum, with relation to the location of an impression roller 19 for co-acting with the drum, which roller serves an important function, when the drum is brought to rest, at which time the clamping bar 18 is 35 directly under the roller 19 (see Fig. 4).

The clamping bar 18 is located in a bore 20, in a reinforced rib portion 21 of the drum, extending from end to end, on the inner side thereof, the bore opened outward to the periphery by 40 a cut 22 made therein, the full length of the bore, for a blade 18' fixed to the bar 18, to swing between side walls 22' and 22'' of the cut, one of which as 22' is used to clamp the end of the master sheet to the drum, indicated at M by 45 broken lines, this clamping wall 22' being in the rear of the wall 22'', in the direction of motion of the drum (see arrow). The wall 22'' when the drum is at rest, as shown in Fig. 4, is used as a stop face, against which the sheets to be copied 50 are registered. The location of the impression roller 19 is not directly over the center of the drum, but somewhat at one side, as shown (see particularly Fig. 4). This enables the entrance of the sheets to be copied under the roller 19, 55 which provides, due to this offset position, a clear path for the sheets to enter under the roller and guided thereby to properly register against the stop wall 22''. It is further a desirable feature to thus locate the roller 19, to be closer 60 to the copy sheet feeding rollers, one of which applies the moisture to the under side of the sheets, since a very light application of the fluid used is quickly evaporated, and loses its effect for taking off the ink from the master sheet, before 65 the copy sheets reach the stop face of the drum and during the time the impression is being made. The bar 18, with its blade 18', is urged against the wall 22' by a spring 18a fixed to the drum, and to one end of an arm 18b by which the 70 bar is rocked to move the blade for entrance of the master sheet (see Figs. 1 and 3). The bar 18, or shaft, as it may be termed, is of a diameter greater than the width of the cut, and provides, when the shaft is in the bore, a stop for the end 75

of the master to limit the movement thereof into the cut, and assures alignment of the master with the drum, and it will be further noted that the clamp bar and shaft are readily removed from the side of the drum.

The feed rollers are supported at the front upper portion of a liquid container, to be as close as possible to the roller 19, the container so arranged to be a complete removable unit (see Fig. 5), including in its entire make-up, a tank-like structure 25, of suitable proportions, to hold a fairly large quantity of liquid, from which to draw by a pumping action to maintain at a constant level a small quantity of the liquid in a shallow basin 26, located closely and somewhat conforming to the curvature of the lower feed roller, indicated at 27, whereby the lower part thereof engages in the liquid to be constantly picking up the liquid as the roller is rotated, and the amount brought to the top of the roller is regulated by a contact roller 28, mounted at the front thereof. The basin has a forward extension 26' to catch the drip from the contact roller, that is squeezed away as a surplus, the basin discharging its overflow over the edges of the shallow basin. The roller 27 is rotatably mounted in bearings in the end walls of the container, one of which, indicated at 29, at one end, as in Fig. 7, and the other, carried by a plate 30, both bearings being fixed by screws to the end walls of the container. The roller 27 is supported on a shaft 31, which extends outside the container at each end, and is here shown driven by a friction drive, indicated at F, including a pinion 32, fixed to a sleeve 33 of a disc 34 loosely mounted on the shaft, a friction washer 35, of suitable material, interposed between the disc 34 and a disc 36, slidably mounted on the shaft, and fixed against rotation, by a pin 37, in the shaft, which engages in a slotted part 38 in the hub of the disc 36, and is adapted to rotate the shaft 31 by a regulated pressure applied to the disc 36 against the friction washer and the disc 34, by a spring 36' regulated by a threaded clamp collar 37'. An intermediate gear 39 carried by the plate 30, meshes with the pinion 32, which drives the feed roller 27, and thereby a companion feed roller 27', being the one directly above the moistening feed roller 27, and the regulating roller 28, when the unit is in position on the machine, at which time the gear 39 will engage and mesh with the pinion 6 of the operating handle. The unit is held in place on the machine by screws entering perforated lugs 40, resting on supports 41, extending from the side frames, having threaded bores to receive the screws.

The companion feed roller 27' is supported in suitable bearings 42, that enter slotted upstanding extensions 43 of the container. These bearings ride freely in the slots, to allow the roller to contact with the roller 27, below, to regulate itself to any uneven conditions of this roller, and may be brought to bear with different degrees of pressure on the lower roller by spring controlled arms 44, pivoted at one side of the extensions 43, with overhanging portions to engage the bearings, and thereby force the roller to make contact, and regulated to varying pressures by a spring 45, pivoted at 46, at one end, and the free end, with a hook connection adapted to engage any one of a series of notches in the overhanging portions of the arms, by this construction the roller may be quickly removed, when desired.

To pump the liquid from the supply, to maintain the level in the basin, a pump 47, is at-

tached to the bottom of the container, and close to one side, to make ready connection for operation with a cam 48, carried by the shaft 31, of the roller 27, which engages a rock arm 49, fixed to a short shaft 50, passing through a bearing 51 in the side of the container, and the shaft has an arm 52 inside the container that engages a piston rod 53, slideable in the casing 54 of the pump in a bore 55. The lower end of the bore has an inlet 56, open to the supply of liquid in the container, when the piston rod is elevated, to allow liquid to freely enter under the piston, which opening is closed on the down stroke of the piston, and enters an outlet port 57, communicating with a discharge pipe 58, which feeds the basin, in a manner readily understood.

The rock arm 49 is held in engagement with the cam 48, by a spring, 59. The regulating roller 28, is mounted in bearing members 60, slideable at one end on a pin 61, in a bifurcated slot 62, at the rear end of the bearing members, an angular portion 63 at the forward ends is bored and threaded to receive threaded thumb screws 64, which support this end of the bearings, and the roller is mounted in bores 65 close to the bifurcated ends, so the two rollers will make proper contact with each other. The thumb screws 64 pass through loose bores 66 in the front wall of the container, and are engaged outside thereof, by an equalizer bar 67, which bar is carried central thereof, on an adjustable regulating screw stud 68, threaded at one end, as at 69, supported in a threaded flanged fitting 70 fixed to the center of the container. The stud 68 is reduced to receive the bar, which has a bore 71, to fit loosely on the reduced end of the stud, to rest against a shoulder at the inner side of the bar, and held in position on the stud by an indicator arm 72, the hub of which fits the stud, and between which the bar 67 is freely supported. The end of the stud has a slot for a screw driver, by which the stud may be set to the proper position, with respect to the indicator arm 72, and the hub, on which the arm is supported, is split and is secured by a binding screw 73. The arm is of 45 spring material, and has at its free end a finger piece 74, the inner part thereof pointed to engage in perforations 75, located and suitably spaced in the arc of motion of the arm, provided in the front wall of the container.

Before this construction, the equalizer bar 67, is first positioned between the shoulder of the stud, and the split hub of the arm 72, when this arm is in the first position or perforation, as at 75'. The split hub is then clamped by the binding screw 73, the thumb screws are then rotated, which move the bearing members 60, and thereby the roller 28 to engage with the moistening roller 27, to its greatest contact position, uniformly at each end thereof, thereafter upon the shifting of the spring arm 72, along the perforations, the stud by its threaded end moves the equalizer bar outward, and the bearing members follow, thereby releasing the contact between the rollers to any desired amount. The bar is 65 slightly bowed inward to provide a light spring action, to maintain a rigid action of the connecting members.

The container is also provided with cover plates, one in the rear, indicated at 76, which fits 70 quite close to the roller 27, at one side thereof, so the top of the roller is exposed, and the other side of the plate extends outside the container, and serves to guide the copy sheets under the roller 19, and against the stop wall 22" of the drum. 75

- At the front of the container, a similar guide and cover plate 77 is shown, on which the copies are fed to the rollers 27 and 27', which are the feed rollers.
- 5 At the side of the container a filling spout 78 is fitted with a screw cap 79, through which the container may be filled, and an indicator arm 80 is connected to a short shaft 81, passing through a bearing 82, and an arm connected on the inner side with the shaft carrying a float 83, the indicator will show on the outside of the container, when the desired amount of liquid has been received therein, and when the same is empty.
- 15 By this construction of the copy moistening and feeding means, arranged as a complete unit, I am able to quickly remove the entire unit from the machine, in its fully adjusted operating condition, or replace the same, for any desired 20 reason, together with its complete co-operative mechanism, including the means for instant regulation of the roller 28 by merely shifting the spring arm 72 to increase the film of moisture or decrease the same, carried to the top of the 25 roller 27, to thereby obtain a heavy or light copy, and for the regulation of the companion roller 27' to varying pressures of this roller with the roller 27, by the spring controlled means, and this construction also enables the ready and quick 30 removal of this roller from its mounting.
- The impression roller 19, having, as heretofore described, the preferred location thereof, to one side of the drum, to enable the blank sheets to be guided under the roller, to engage 35 the stop face 22", is further provided with means for rapid adjustment to varying pressures, after first regulation thereof, for uniform contact at each end, and along the length of the drum. Thereafter, as the work continues in making the 40 copies, it will only be necessary to shift a lever, to obtain a change of pressure, between the high and low pressure required. When the master is first applied to the drum, and before imprints have been made therefrom, the carbon or ink, 45 from which the copies are produced, will deliver a heavy imprint to the copy, and at this time a light pressure of the roller 19 will not take so much of the ink from the master, as would be the case under a uniform pressure, as is usually 50 done, throughout the run, for a given number of the copies generally made from one master. I am able to materially increase the number of copies obtained from one master, as stated, by first adjusting the roller 19 to make a uniform 55 contact, as stated, by regulating screws, 84, located in arms 85, fixed to a rock shaft 86, mounted in bearings of the frame, the arms overhanging the bearing members 87, in which the roller 19 revolves, and the bearings are movably carried, in runways of the frame, to enable the roller to make close contact with the drum, in all 60 positions thereof, the bearings being held in position against lateral outward movement by the regulating screws engaging in slightly recessed 65 pockets at the top of the bearings in which the ends of the screws enter. By lifting the arms, the bearings are readily removed from the ends of the roller and withdrawn outward of the frames, and thereby the roller removed from the 70 machine. Under each bearing 87, a spring 88 supports the bearings against the screws 84 (see Figs. 1 and 3). This shaft 86 is rocked by a spring arm 89, controlled by a cam 90, of a regulating arm 91, pivoted at 92 to the side frame 2. 75 The arm has a spring detent pin 93, with a finger piece for withdrawal of the pin from perforations 94 in a sector of the side frame for positioning the arm and cam, to exert more or less pressure to the spring arm 89 and thereby the roller 19. By this arrangement, when the parts have been 5 carefully regulated, as stated (which only needs to be done once, for a permanent adjustment thereof until some change in type of work or condition of the machine occurs), it will only be necessary thereafter to move the arm 91 along 10 the perforations of the sector. When the master is first applied, the pressure is at its lowest pre-determined position, and the arm 91 is set, in the lowest pressure perforation of the sector, and as the work progresses in producing the copies, 15 the arm is changed to increase the pressure as required. By this means a greater number of copies may be produced from one master, since the master is not forced to give a greater amount of ink than is required to maintain a uniform 20 shade and color of the imprint taken by the copies. The arm 91 also may be shifted to a position along the sector to free the screw ends of the arms 85 from the bearings, so the bearings may be removed from the ends of the roller, as 25 before stated.
- To feed the copies to the feed rollers 27 and 27', by hand, or automatically, as may be desired, a feed table 95 is mounted on forward extensions 96 of the side frames 2 and 3, the feed table preferably being carried by a bar 97, attachable to the extensions, on which the table is movable for adjustment from side to side, and arranged to be readily applied, and removed from the machine. As here shown, the bar is held at each end by a 35 thumb screw 98, tapped into the extensions. The table, see Fig. 8, in its preferred form, is made up, by a plate 99, forming the bottom, of suitable width, bent up at the delivery end, by a right angle bend upward, as at 100, and again bent forward to provide an apron-like portion 101, that when in position, as in Fig. 4, is resting over the front portion of the plate 77 of the container 25, over which the sheets are guided to the feed rollers. At the sides of the plate 99, angle members 40 102 are attached to the plate the full length thereof, to provide the side walls of the box-like structure of suitable width, between which, and a pair of adjustable side plates 103, the pile of 45 copy sheets are guided, the front ends thereof 50 engaging the wall 100. The plates 103 have projecting studs 104, that engage in bearing hubs 105, for adjustment of the plates to varying widths of copy paper, and for true alignment with the front ends of the sheets with the feed rollers, and 55 the hubs have set screws to bind the studs in their final adjusted position. A complement of 60 spring members 106, fixed to the extreme front end, on the inner top side of the table, the free ends thereof extending upward and joined by a 65 cross bar 107. The springs are so arranged as to support a pile of sheets and to yield under the weight of the full pile to assume a flat position on the plate 99, but when the sheets are removed, one by one, will gradually raise the pile, till the 70 lowermost sheet is elevated to make slight contact with the under side of a cross bar 108, best seen in Fig. 4, this bar being fixed to the top of the angle members 102. The spring members 75 106 are active only when the machine is set for automatic feeding, and when feeding by hand these springs are pressed downward, to any degree desired, and locked, so the table will be free for handling the blanks to move them forward under the cross bar 108, into the bite of the roll- 75

ers 21 and 27', which at this time will be momentarily stopped, or if desired continuously rotated. The spring members are held in the locked position by a threaded rod 109 extending downward from the center of the cross bar 107, passing through an opening in the table, and a thumb nut turned up on the rod, to hold the springs down. The thumb nut may be turned back, to the end of the rod, which is upset to prevent the nut from leaving the rod, when the springs are used for automatic feeding.

The power of the spring members 106 may be regulated to increase or decrease the lifting action, by a bar 108', positioned under the springs and adjustable in slots 106" in the table, in which the bar is moved forward and back and locked under the table by nuts on the clamping screws 108a, or in any desired manner.

The table may be shifted, for side adjustment thereof, along the bar 97, slideable on the bar in bearings 97' fixed to the table and clamped by a clamp screw 97''. The front wall 100 of the table is provided with a thin flexible rubber 101', the top of which extends to and lies over the rounded corner of the apron 101 and held by a plate 110, to the wall 100, as by screws, the rubber acting as a separator, to prevent feeding of more than one sheet. The friction drive F, for rotating the feed roll 27, and thereby the roll 27' by contact therewith, is so regulated to drive these rollers for continuous rotation, as before stated, for automatic feeding of the copy sheets, or the rollers may be intermittently driven for hand feeding, the latter being done by providing the disc 36 of the friction member with teeth 111 on its periphery, to be engaged by a tooth 112, on an arm 113, of a rock lever 114, pivoted at 115, on the outer side of the frame 3 (see Fig. 9), the lever operated by a cam 116, on a cam shaft 117 which shaft is driven by a gear 118, fixed on the shaft and meshing with the gear 8, of the train. This lever 114 is arranged so it may be held away from the cam, by a lock arm 119, and is also pivoted on the frame at 120. One part of the arm, as 121, when the arm is in one position thereof, will engage the arm 113, and hold the tooth 112 out of engagement with the teeth of the disc 36, and the lever 114 free of the cam, and thereby the friction drives the roller 27 continuously, and when the lock arm 119 is shifted, to the dotted position, the cam is engaged by the lever 114, the cam of suitable shape, at the proper time, will bring the tooth 112 to engage the teeth of the disc 36, and hold the roller 27 from further rotation, till the copy sheet has been inserted into the bite of the feed rollers, when the cam will release the engaging teeth and feed the copy to the drum stop 22". An automatic copy-sheet feeding means is provided, to feed and separate the copies for single sheets, from the top of a pile of blanks to the feed rollers in a manner to reach the feed rollers at a predetermined time. In case the drum is being operated intermittently, this should be as soon, or about the time the drum comes to rest, during which time the feed rollers will propel the sheets to the stop 22" of the drum, preferably just a fraction of time before the drum again starts to rotate, to be sure that the front end of each sheet contacts with the stop to assure perfect register of the sheets. This is accomplished by the proper shape and timing of a cam, adapted to control the lifting and descending movement given a constantly rotating feed wheel. When the drum is being continuously driven, the feed wheel may be adjusted to feed the sheet

somewhat sooner. The feed wheel, indicated at 125, is mounted on a stud 126, carried by one arm, as 127, of a rocking frame 128, preferably formed of material bent to provide a U-shaped portion 129, and at its other end an arm 130, between which the frame is supported, to rock in bores 130', on the outer ends of bearings 131 secured to brackets 132 fixed to the bar 108, of the table 95. The free end of the arm 130 of the frame 128 is again bent, as at 133, to reach outward to the side of the frame 2, where it is engaged by an upright bar 134, the top of which engages a pin 135 at the end of the arm 133, to rock the frame to lift and lower the feed wheel, the bar 134 being actuated by a cam lever 136, connected by a pivot 137, to the lower end of the bar (see Fig. 3), the upper end being guided to slide in a capped bearing 134' and controlled in its movements by a cam 138, fixed on the shaft 117. The cam, of suitable shape, may be adjusted to lift and lower the feed wheel in proper timing to engage the uppermost sheet of the pile of blanks, and propel the same to the feed rollers. The feed wheel 125 is continuously driven, as here shown, by a chain drive (best seen in Figs. 1 and 3), the chain 140, driven by a sprocket wheel 141 rotatably mounted on a stud 142, on the inner side of the frame 2, which sprocket has attached thereto a gear 143 and driven by a gear 144 fixed to the shaft 117, to drive the chain in the direction indicated by the arrow. The chain drives a small sprocket 145 fixed to a sleeve 146, that revolves on a stud 147, secured to the side frame 2. The sleeve is slotted at the front end, as at 148, to make a coupling connection with a shaft 149, that is rotatably supported in the bearings of the bracket 132 on which the frame 128 rocks, and the shaft at its outer end has a small sprocket 150, which drives a short chain 151, over a sprocket 152 attached to the end of the feed wheel 125, by which the same is driven. The feed wheel as here mounted on the rock frame may be swung upward to an upright position to be out of the feeding position and clear of the entrance of the sheets, over the apron 101, and under guide members 101', when feeding the sheets by hand.

From the foregoing it will be understood, that when the machine is fed automatically, the sheets are fed to the feed rollers from the top of the pile of blanks, that are elevated by the springs 106 to have the uppermost sheet of the pile in position to ride over the rounded edge of the apron 101 of the table 95, and here separated, preventing the sheets under the top sheet, by contacting with the rubber facing 100', from moving forward with the uppermost sheet. The machine by this arrangement is quickly set to feed by hand, by simply lifting the feed wheel to an upright position, as stated, shifting the arm 119 to the dotted line position, so the cam lever 114 will engage the cam 116, and thereby the tooth 112 of the lever will engage the teeth 111 of the disc 36, to stop the feed rollers for the interval of time required to insert a sheet into the bite of the rollers, which will then rotate again, in proper timed relation to feed the sheets to the drum stop.

It is found in practice particularly important in the making of high grade copies, that the rollers used for proper and uniform impressions with one another, as is required in this class of work, be constructed of suitable material, and yet be produced at a low and competitive cost. The roller 19 is of rubber, of suitable resiliency to quickly respond to the different adjustments given this roller. The roller 27, as usually constructed of

porcelain is expensive, since it must be carefully mounted on a shaft, the porcelain of tube formation is generally carried on a shaft, surrounded by a cement filling to prevent breakage of the tube, also requiring careful grinding and polishing, making an expensive roller to produce. As here shown, the roller 27 is preferably constructed by mounting a tube of suitable material adapted to withstand the moistening material used in this type of machine, with which this roller is constantly saturated; one form thereof I have successfully employed, as shown in Fig. 11, consists of a steel tube, having hubs 27a, forced in the ends thereof, bored to receive the shaft 31, which is held by a binding screw 27c, for quick removal, when desired, from the container, when the container is in the machine, from the side thereof. The tube 27 is highly polished and plated, which prevents corrosion, and provides for free spreading of the moistening fluid thereon. Another form of tube successfully used and mounted in the same manner just stated, consists of a molded product known as Micarta, in the electric trade, having all the qualities required for proper distribution of this moistening liquid herein employed. The roller 27', that contacts with the roller 27, is usually made of felt, indicated by stippling, as best seen in Figs. 3 and 4, and may be made of sponge rubber. In either form, the material is formed into washers and applied on the shaft to support the same, packed on the shaft to provide firmness and proper resilience, and held in such position by a nut and washer at each end of the shaft, the surface is ground to be true, to co-act with the roller 27, to yield and ride thereon, to conform to any slight variations between the two rollers, and press the copy sheets under regulated pressure thereto for even distribution of the moisture to the underside of the copies, which results in perfect copies taken from the master. The roller 28, for regulating the moisture, may also be of felt, or rubber similar to the roller 27', but preferably of a more resilient quality, for close regulation thereof with the roller 27, and somewhat more absorbing than the roller 27', since as stated when the roller 27 comes to rest, as which time the roller 27 is in position to receive a copy sheet, the roller 28 also stops, and at this time any moistening material that is on the rollers runs back, and lodges between the two rollers during the stopped position thereof, and this accumulation, while it may be slight, will, when the rollers are again started to rotate, be brought up and transmit a heavier coating at this particular portion of the roller to the copy sheet, and a heavy imprint at this place on the copy sheet would be made, but this trouble is entirely obviated by the absorbing quality of the roller.

In Fig. 12, a modification is shown of the means for supplying the liquid from the supply in the container to the underside of the roller 27, and may be regarded as the preferred form of this means, over that of the pumping action into the basin in which the roller 27 revolves, as heretofore described. Here, instead of the pump, and by omitting the basin, the mechanism is much simplified. An endless belt 153, preferably of rubber, is suspended to the bottom of the container, and driven by the roller 27, by a contact roller 154, over which the belt travels and held in close engagement with the roller 27, the roller 154 is supported on journal ends in bearing pockets of spring hangers 155, located at each end of the roller, the hangers fixed to the rear

wall of the container, and are of proper tension to hold the roller and the belt to engage the roller 27, to be frictionally driven thereby. The roller 154 is not directly under the roller 27, but preferably as shown somewhat forward thereof, and as close to the regulating roller 28, without touching the same, this position thereof permits of rotating the roller 27 in the reverse direction, which is often done by turning the crank handle in the wrong direction. When this is done, it is found that the roller and belt do not revolve and no liquid is carried up from the supply. When the belt is driven in the proper direction, as shown by arrows, a heavy film of liquid is constantly applied, to the bottom of the roller 27, in excess of the amount required, but I provide for regulation thereof by the roller 28, between the predetermined limit points, as hereinbefore stated.

In Fig. 13, I show a modification in the gear train, to provide for continuous rotation of the drum, and the feed and moistening rollers 27 and 27'. While it is the usual practice in copying machines to drive the drum intermittently, with my improved stop face 22' of the drum, formed by the cutout 22, for the master clamping bar to swing in, I am able to provide for proper register of the copy sheets with the master while the drum is in rotation, by so timing the lowering movement of the feed wheel 125, to move and feed the sheets forward to the moistening and feed rollers, which rollers continue the feeding of the sheets to the drum, while the feed wheel 125 at this time is elevated and ready to repeat the next feed operation, during which time the forward end of the sheet being fed is moved against the stop. A slight variation in the feeding of sheets is likely to occur, this, however, is taken care of here, by the cutout portion 22 of the drum, being quite wide, the sheet is so timed to enter the cut, as the same revolves to the position, as here shown, to open a passage under the roller 19 to guide the end of the sheet therein, and this may take place any time during the time the opening is thus passing under the roller 19, allowing of a difference, of about three sixteenths of an inch, variation of the front ends of the sheets to engage the stop, this difference is taken up as the drum advances, otherwise in some cases that portion of the sheet would be drawn tight between the feed rolls and the drum, and in other cases the sheet would be loose and a loop would form, as indicated at L. The gear 6 of the train, driven by the hand crank handle, meshes with the gear 8, as an intermediate gear to drive the gear 10a to rotate the drum, for continuous movement, by thus arranging the gear train, the cam shaft 118, as shown in Fig. 4, is placed between the drum and the container 25, indicated at 118' to be clear of the drum, and on this shaft the gear 8 is mounted, instead of the stud, as heretofore, to provide this position of the shaft, and is driven by the gear 8, on which the cam 138 to lift and lower the feed wheel is mounted, and by slightly rearranged position of the connections, and the chain 140 to drive the feed wheel.

Fig. 14, also a modification, shows the same general arrangement of the gear train, as just described with respect to Fig. 13, to rotate the drum continuously. Here, however, the machine is especially adapted for hand feeding and the friction drive F, of the feed rollers 27 and 27' is employed to momentarily stop the feed rollers, to provide time to insert the copy sheet to be fed

into the bite of the rollers, which at the proper moment will again rotate and feed the sheet to the drum stop, the distance from the rollers to the drum, is quite close, and a slight advance 5 movement of the feed rollers, is obtained by the proper timing of the cam 116, on shaft 118, to operate the connections, as here arranged, to suit the position of the shaft, the operation otherwise being as hereinbefore described.

10 In Figs. 15 and 16, certain modifications of the moisture regulating means are shown. Instead of the roller 28, as heretofore described, I may employ a non-revolving contact member 160 of any suitable material, such as felt (see Fig. 15), in 15 the form of a pad to engage the roller 27, with the same adjusting means to vary the tension against the roller 27, and wipe the roller, in a manner readily understood, to carry a heavy or light coating of the moisture to the top of the roller 27, to be applied to the copies. The felt pad may be so shaped as to engage the face of the roller the full length thereof with a comparatively wide front face 161, and at the top of the pad taper downward and rearward from the roller to provide 20 a drain from the roller 27 at the time this roller comes to a stop to insert a copy sheet to be fed, as hereinbefore referred to. Another form of this wiping and regulating means is shown in Fig. 16, here the regulating contact is 25 made with a yielding flexible strip 162 of metal, having a perfect draining position, placed at the angle shown, and the strip will yield to close contact along the full length of the roller, and the strip being carried in any suitable manner to 30 be regulated, such as already disclosed.

35 The operation of the invention has been referred to in what has been above said, and it is believed the same will be entirely plain without further description.

40 Certain of the advantages of the invention have also been pointed out in what has been above said, and others will be readily seen without further description.

I do not limit myself to the particular details 45 of construction which have been set forth in the foregoing specification and illustrated in the accompanying drawings, as the same refer to and set forth only certain embodiments of the invention, and it is obvious that the same may be 50 modified, within the scope of the claims hereof, without departing from the spirit and scope of the invention.

Having thus described my invention, what I 55 claim as new and desire to secure by Letters

Patent is as follows:

1. A copying machine, comprising a supporting frame, a drum and an impression roller co-acting therewith, a gear train to rotate the drum and said roller intermittently or continuously, 60 means carried by the drum, to clamp a master sheet thereto, from which copies are produced, and provide to gauge stop for registration thereof, close to the clamped end of the master, including a clamp bar fixed to a rock shaft located in a bore longitudinally of the drum, adjacent the periphery thereof, said bore having a cutout extending outward of the drum the full length thereof, and of a width less than the diameter of the shaft in the bore, providing said cutout with opposing walls, between which the clamp bar is adapted to swing, for clamping the master sheet between one wall and the bar, with the end of the master engaging the shaft to limit the movement thereof into the cut, which wall is 70 in the rear of the wall, in the direction of mo-

tion of the drum, said other wall being a stop wall, against which the copy sheets engage for registration thereof, said impression roller, located forward of a vertical line drawn through the axis of the drum to provide an open passage 5 under the roller during the time the cutout passes under the roller for the entrance of the copy sheets to engage the stop wall of the drum, during the rest period or continued rotation of the drum.

10 2. A copying machine, comprising a drum, and an impression roller co-acting therewith, supported for rotation in spaced side frames, said roller mounted in slideable bearings for adjustment of the roller to varying contact pressure 15 positions with the drum, and removable outward of the side frames for the removal of the roller from the machine, means to move and regulate the bearings under a yielding pressure and thereby the roller, including a rock shaft 20 pivotally located in the side frames at one side of the bearings to be parallel with the roller and having overhanging arms fixed to the shaft, with adjusting screws in the ends of the arms to engage the bearings for independent adjustment 25 of the bearings to obtain first a uniform pressure of the roller with the drum at both ends and along the length thereof, means to rock the shaft for instantly changing the said regulated uniform pressure between predetermined and 30 varying pressure positions of the roller with the drum and a position thereof to free the arms from the bearings to enable the withdrawal of the bearings outward of the frames and thereby 35 the roller from the machine, including a spring arm fixed to one end of the shaft, and having an operative engagement with a cam face portion, or its equivalent, of an oscillating member pivoted to the frame, and an arm thereof by which it is shifted for adjustable positions there- 40 of along a sector, and means to lock the arm in any of said positions.

3. A copying machine, comprising a drum and an impression roller coacting therewith, a liquid container carrying means to feed copy sheets to 45 the drum, moisten the underside thereof by one of a pair of feed rollers supported for rotation in the container, one roller above the other, the lower one of which supplied with liquid by 50 picking up at the lower portion thereof by revolving in a shallow basin located at the top of the container, the basin being supplied from the main supply to overflowing by a pump in the container, operated by a connection from the lower feed roller, means to regulate the quantity 55 of liquid carried to the top of the roller to be transferred to the copies, and means to drive the lower feed roller, intermittently, or continuously, and means adapted to instantly change the drive from continuous to intermittent rotation, sub- 60 stantially as specified.

4. A copying machine, of the class specified, comprising a drum, and an impression roller co-acting therewith, means carried by the drum to clamp a master thereto, said means connected 65 with means to provide a stop face against which copy sheets are registered with relation to the position of the master, and by the location of said impression roller, set forward to engage with the drum at one side of the axis thereof, for sheets 70 to be guided under the roller to engage the stop, means to feed the copy sheets to the drum, and apply a moisture to the underside thereof, said means including a liquid container embodying a structure removably attached to the machine as 75

- a complete unit, having means to feed copy sheets between a pair of feed rollers, one of which revolves in a shallow basin, at the top of the container, supplied with liquid to overflowing capacity, by a pump within the container from a main supply carried by the container, said overflow returned to the supply, means to drive the said feed roller revolving in the basin intermittently, to stop the rotation of the feed roller 10 during a short interval to feed a copy sheet to the rollers, means connected with the said driven feed rollers to operate the pump, means to regulate the quantity of liquid transferred by the roller to the sheets, and means to instantly change 15 the quantity so regulated between predetermined limits thereof from a greater to a lower quantity, and means to regulate and vary the contact pressure between the pair of feed rollers substantially as specified.
- 20 5. A copying machine, of the class specified, comprising a drum, and an impression roller co-acting therewith, means carried by the drum to clamp a master thereto, said means connected with means to provide a stop face of the drum against which copy sheets are registered with respect to the position of the master, and by the location of said impression roller, set forward of the drum to engage with the drum at one side of the axis of the drum, for sheets to be guided 25 under the roller to engage the stop, means to feed the copy sheets to the drum, and apply a moisture to the underside thereof, said means including a liquid container embodying a structure removably attached to the machine as a complete unit, having means to feed copy sheets between a pair of feed rollers, one of which revolves in a shallow basin, at the top of the container, supplied with liquid to overflowing capacity, by a pump within the container from a main supply 30 carried by the container, said overflow returned to the supply, means to drive the said feed roller revolving in the basin continuously or intermittently, means connected with said feed rollers to operate the pump, means to regulate the quantity of liquid transferred to the sheets, and means to instantly change the quantity so regulated, between predetermined limits thereof from a greater to a less quantity, and means to regulate 35 and vary the contact pressure between the pair of feed rollers, carried by the container, means to automatically feed the copy sheets to the feed and moistening rollers in timed relation whereby the feed rollers will feed the copies to the drum stop.
- 40 6. In a machine of the hectograph type, comprising a drum and impression roller co-acting therewith, means adapted to moisten, in adjustable regulated quantity and feed the copy paper to said drum and impression roller, including a structure, embodying as a complete unit, for removable attachment to the machine, a liquid container supporting a pair of feed rollers, one above the other, the lower one of which is supplied with liquid from the container, by an end-45 less belt suspended in the container to pick up from the bottom thereof, the liquid and transfer the same to said lower feed roller, said belt yieldingly supported on a roller, over which it travels, and driven by contact with said lower feed roller, a regulating roller engaging the said lower feed roller, located between the contact portions of said pair of feed rollers and said liquid applying belt, means to adjust the regulating roller to uniform contact with the lower feed roller, means 50 to vary the contact pressure of said roller so adjusted, and means to lock the roller in said varying contact positions.
7. In a machine of the hectograph type, comprising a drum and impression roller co-acting therewith, means adapted to moisten and feed the copy paper to said drum and impression roller, including a pair of feed rollers, mounted one above the other, in a liquid container, the lower roller of non-porous material, supported for rotation in bearings located in the end walls 55 of the container, and above a supply of liquid therein, means to drive the roller, means to interrupt the rotation of the roller, to provide time to insert a copy into the bite of the feed rollers prior to feeding the copy between said rollers, means driven by the lower feed roller to pick up liquid from the supply in the container, and transfer the same to the lower feed roller, including an endless belt suspended in the supply to the bottom thereof and mounted on a carrying roller over which the belt travels whereby the belt engages the said feed roller, means to vary the contact pressure of the top feed roller, with the lower roller, including sliding bearings in which the roller is mounted, regulating arms 60 engaging the bearings over the top thereof, the arms extending forward, and having notches, for the ends of pull springs pivoted to the container, and adjustable along the notches, for applying more or less tension on the roller.
8. In a copying machine, comprising a suitable frame, adapted to support one portion of a mechanism of a complete machine, normally not removable, and a removable portion of the mechanism, said normally non-removable portion including a gear train, having a driving gear fixed to a driving shaft, to operate the train, an intermediate gear, meshing with said driving gear, fixed on a shaft, which shaft serving as a cam shaft preferably extending across the machine 65 and located forward of said normally non-removable mechanism and between said removable portion and said normally non-removable portion, said intermediate gear meshing with a gear fixed to a drum for continuous rotation thereof, by said drive gear, and an impression roller, co-acting with and driven by the drum, said removable mechanism including a liquid container embodying a structure adapted to support, as a complete unit, attachable to the machine, the 70 mechanism for feeding copy sheets to the drum, deliver to the underside thereof a regulated uniform coating of the liquid from the container, adapted to be first regulated to uniform distribution thereof and deliver a quantity greater than 75 required, and a separate means to regulate the quantity between predetermined points of adjustment, for a heavy or light coating thereof, to the copies passed through a pair of feed rollers, the lower one of which supported for rotation above the liquid, in the container and supplied with the liquid from the bottom thereof by a traveling belt suspended therein, means to drive the lower feed roller intermittently or continuously, including an intermediate gear, rotatably mounted on the container, and meshing with a continuously driven gear being one member of a friction member carried by the shaft of the lower feed roller, by which the roller is driven, and means carried by the non-removable mechanism to engage the friction member to stop the feed rollers and release the same in timed relation to feed the copies to the drum.
9. A copying machine comprising a drum, having a stop face against which copies are regis- 75

tered, and an impression roller co-acting therewith, a pair of feed rollers adapted to feed the copies to the drum and the stop, the lower one of which is adapted to receive liquid from a supply, to be delivered in regulated quantity to the underside of the copy sheets, during the feeding thereof, means to drive the lower feed roller intermittently or continuously, including a friction drive member, providing in its preferred form, a continuously driven gear loosely mounted on the shaft of the roller, said gear attached to a disc forming one part of the friction member, for coacting with a companion disc slidably fixed to the shaft, a friction washer interposed between said discs, and provided with means to regulate the power of the friction drive, means to continuously drive the gear and said disc and thereby the roller, means to intercept the rotation of the feed roller, including teeth on the periphery of the said disc attached to the gear, adapted to be engaged by a tooth of the intercepting means and thereby stop the rotation of the roller, means to operate the intercepting means, in timed relation to feed a copy sheet into the bite of the feed rollers and release the same in proper timing whereby the copy sheet will be fed to the said stop of the drum, means connected with said intercepting means, adapted to shift the position thereof, from an active position wherein the said feed rollers are intermittently driven, and when in the inactive position the feed rollers are continuously driven.

10. A copying machine, comprising a drum and an impression roller co-acting therewith, said roller located to engage the top of the drum, forward of a vertical line drawn through the center of the drum, means to drive the drum continuously and thereby the roller, said drum having a master clamping means including a rock shaft provided with a clamping bar located in a bore adjacent the periphery and longitudinally of the drum, a cutout portion extending outward of the bore in which the bar may rock and clamp a master sheet against one wall of the cut, and the other wall provide a stop face against which sheets to be copied are registered, means to feed the copies to the drum and moisten the underside thereof, including a pair of feed rollers adapted to be either continuously or intermittently driven and means to drive the same, means to automatically feed the sheets from the top of a pile of blanks in timed relation to propel the sheets to said feed rollers, and continue the feeding action by the feed rollers to the drum stop, in a slightly advanced timing action of the said feed members, whereby the leading end of the sheets fed will engage the drum stop while the stop is passing under the impression roller to guide the sheet to the stop.

11. In a copying machine, comprising a pair of feed rollers, rotatably carried at the top of a liquid container, one of which supplied with liquid, at one side thereof, by a traveling endless belt adapted to pick up liquid from the bottom of the container, to use the full supply therein, with an amount greater than an amount delivered over the roller to copy sheets passed between the rollers at another portion thereof, means to regulate the amount so delivered to said copies, located between said delivery portion, and that portion so receiving the supply, including a contact member adapted to engage the roller under varying degrees of tension, to wipe the roller, said member having its upper contact end, close to the roller, tapered outward and down-

ward away from the roller to drain the accumulation over the roller brought to the top thereof, which tends to run back when the roller is brought to a stop.

12. In a copying machine, comprising a supporting frame, a drum and an impression roller co-acting therewith, a gear train to rotate the drum intermittently or continuously, means carried by the drum, to clamp a master sheet thereto and means connected with said means, to provide a gauge stop for registration of the copy sheets, close to the clamped portion of the master, both said means including a clamp bar fixed to a rock shaft located in a bore longitudinally of the drum, adjacent the periphery thereof, said bore having a cutout extending outward of the drum of less width than the bore, the full length thereof, providing said cutout with opposing walls, between which the clamp bar is adapted to swing, for clamping the master sheet between one wall and the clamp bar, the shaft of which limits the inward movement of the master into the cut, said wall being the rear wall of the cut in the direction of motion of the drum, said other wall being a stop face, against which the copy sheets engage for registration thereof, said impression roller, located forward of a vertical line drawn through the axis of the drum, to provide an open passage under the roller for the entrance of the copy sheets to engage the stop.

13. A copying machine, comprising a drum adapted to hold a master, an impression roller co-acting with the drum, and a complete unit comprising a liquid container, supporting mechanism for feeding copy sheets to the drum and delivering to the underside thereof a regulated uniform coating of the liquid from the container, said container and mechanism being arranged and assembled for convenient unitary attachment to and removal from said machine without substantial disassembling of any other parts thereof.

14. A copying machine, comprising a drum and an impression roller co-acting therewith, and means adapted to moisten and feed the copy paper to said drum and impression roller, including a liquid container, a pair of feed rollers, and an endless belt adapted to pick up liquid from said container and transfer the same in regulated quantity to one of said feed rollers.

15. A copying machine, comprising a drum and an impression roller co-acting therewith, means to feed sheets to be copied to the drum, and apply moisture in regulated and predetermined quantity instantly adjustable from a heavy to a light application thereof, to the underside of the sheets to be copied, including a pair of feed rollers with adjusting means to regulate the pressure between the rollers, together with the moisture regulating mechanism therefor, supported by a structure embodying a liquid container adapted for removal from the machine, with the operating parts thereof in their fully working adjusted position as a complete unit, said container having bearings in the end walls to suitably support the feed rollers one above the other, the lower one of which fixed to a shaft, removable from the side of the container, for the removal of the roller, and the upper roller carried in bearings slideable in runways in the container, to make contact with said lower roller, means within the container, and actuated by said lower roller over which the moisture is transferred to the copies, including a traveling endless belt, adapted to lift a greater supply of liquid than required from

- the bottom of the container, to be acted upon by said regulating means before the moisture is transferred and applied to the sheets, closure plates to close the top of the container, over which the copy sheets are guided to and from said lower roller and under the companion feed roller, one plate at each side thereof, with a portion of the roller exposed, over which the copies are moistened and fed to the drum.
16. A copying machine, comprising a drum and an impression roller co-acting therewith, a liquid container embodying a structure adapted as a complete unit removably attached to the machine, carrying the complete operative mechanism in the fully operating adjusted position thereof, including means to feed copy sheets to the drum, means to regulate the tension between the feeding means, means within the container to pick up liquid from the bottom of the container and transfer the same to the copies, means to regulate the liquid picked up, to a uniform and even distribution thereof, before transferring the same between the said feeding means, means to instantly regulate the uniform distributed liquid from a heavy to a light distribution thereof, between two predetermined pressure positions of the regulating means, and intermediate positions thereof, and means to control and lock the regulating means at said predetermined points and intermediate positions thereof, said means located outside the container, for ready manipulation.
17. A copying machine comprising a drum and an impression roller co-acting therewith, a liquid container embodying a structure adapted as a complete unit removably attached to the machine, carrying the complete operating mechanism in the fully operating adjusted position thereof, including means to feed copy sheets to the drum, and moisten the underside thereof, and means to regulate the tension between the feeding means, said moistening means, including a traveling belt enclosed within the container, adapted to pick up liquid from the bottom of the container and apply the same in quantity greater than required, to said feeding means at a position before and between which the liquid is transferred to the copies, means to regulate the liquid so picked up, to a uniform and even distribution thereof to said feeding means, said means consisting of a movable contact member adapted to engage with the liquid, the contact member carried in sliding bearings, one at each end thereof, said bearings supported in the container, and having adjusting screws threaded therein and extending outward of the container to engage the ends of an equalizer bar, by a grooved headed part of the screws fitting in bifurcated portions thereof, for uniform adjustment of the contact member with said feed means for even distribution of the liquid, and means to instantly regulate the quantity between two predetermined positions of regulation, for a heavy or light distribution, and positions intermediate thereof, including a stud threaded into the container on which the equalizer bar is loosely mounted centrally thereof, against a shoulder of the stud and between a hub of a spring arm fixed to the stud to rotate the same for movement of the bar, and thereby the contact member, for varying the position thereof, from one to the other and between said predetermined regulating positions, said arm controlled at its free end by engaging in any one of a series of perforations to hold the arm and its connected parts in locked relation.

18. A copying machine of the class specified, comprising a drum and an impression roller co-acting therewith, a liquid container carrying means to feed copy sheets to the drum, moisten the underside thereof by liquid transferred to the copies over one of a pair of rollers supported for rotation in the container, one roller above the other, the lower one over which the liquid is transferred supplied with the liquid by a traveling endless belt within the container picking up the liquid from a main supply from the bottom of the container, said belt driven by said lower roller, means to regulate the quantity of liquid transferred to the copies, means to drive the lower roller intermittently or continuously, and means to instantly change the drive from continuous to intermittent rotation.

19. A copying machine, comprising a drum and an impression roller co-acting therewith, means carried by the drum to clamp a master thereto and provide a stop face for copy sheets to engage, including a bore lengthwise of the drum, adjacent the periphery, a cutout portion outward of the bore to receive therein a rock shaft, the diameter of which is greater than the width of the cutout, and said shaft having a clamp bar attached, adapted to swing between the walls of the cut, to clamp a master sheet to one wall of the cut, and limit the inward movement of the master into the cut by engaging the end thereof against the shaft, as a stop, a liquid container embodying a structure removably attached to the machine as a complete unit, including means to feed the copy sheets to the drum and moisten the underside thereof, means within the container to pick up liquid from the bottom of the container to be transferred by the feeding means to the copies, means to regulate the liquid to an even distribution thereof, and means to instantly regulate the liquid between two predetermined positions, from a heavy to a light coating thereof, and means to regulate and vary the contact pressure of the feed means carried by the container, means to automatically feed the copies to said feeding means, which in turn feed the copies to the drum stop, in timed relation.

20. In a machine of the hectograph type, comprising a drum and an impression roller co-acting therewith, means adapted to moisten in adjustable regulated quantity and feed the copy paper to said drum and impression roller, including a structure embodying as a complete unit for removable attachment to the machine, a liquid container supporting sheet feeding means, including a pair of feed rollers, one above the other, the lower one of which is adapted to supply the underside of the copies with liquid from the container, by a traveling endless belt enclosed in the container, the lower end suspended in the liquid, to pick up from the bottom thereof, to be transferred over said lower roller to the underside of the copy sheets, means to drive the belt by said lower roller, a regulating roller, located in front of the lower roller, adapted to contact with the liquid prior to the transferring thereof to the copies, to strip the liquid to uniform and varying quantities, means to instantly vary the contact pressure of the regulating roller so adjusted, and means to lock the roller in said varying contact positions.

21. A copying machine, comprising a drum, means to feed copy sheets to the drum and moisten the underside thereof, by liquid supplied from the bottom of a container, to use the full supply therein, the liquid picked up by a

traveling belt, enclosed in the container, adapted to transfer the same to the feeding means, said container removably attached to the machine as a complete unit, carrying said feeding and moistening means, and means to regulate the liquid before it is received by the copies, by a first regulation thereof for a uniform and even distribution in a quantity greater than required, and means for instantly reducing the quantity between two predetermined quantities from a heavy to a light application thereof, and means to regulate the pressure between said feeding means.

22. A copying machine, comprising a drum and an impression roller co-acting therewith, means to feed copy sheets to the drum, including a structure embodying as a complete unit for removable attachment to the machine, including a liquid container supporting a pair of feed rollers, one above the other, the lower one of which carrying liquid from the container supplied by a traveling belt enclosed within the container, one end thereof suspended in the container to pick up liquid from the bottom thereof, and transfer the same to and over said lower roller, said belt driven by said lower roller, and means to support the suspended portion of the belt in spaced relation from the upper portion, means to drive the lower roller intermittently, to stop and start the rotation thereof at a time independently of the timing of the intermittent rotation of the drum, and means carried by the container to adjust the tension between the feed rollers.

23. A copying machine, comprising a drum and an impression roller coacting therewith, spaced side frames between which the drum and roller are mounted, said roller engaging the drum above and forward of a vertical line drawn through the axis of the drum, to provide an opening under the roller with relation to a cutout portion of the drum, when said cutout is in position under the roller, a master clamping means adapted to clamp the master against one wall of the cutout, and the other wall of which forms a stop face against which copy sheets are registered, to be close to the clamped end of the master, means to feed copy sheets to the drum, means to regulate the pressure of the impression roller for uniform alignment at both ends thereof with the drum, including sliding bearings in which the roller is mounted, such as open runways of the frames, a rock shaft rotatable in the said frames, located close to and parallel with the roller, arms fixed to the shaft overhanging the bearings, with adjusting screws to engage the bearings, the ends of which enter in recessed pockets therein, to hold the bearings in their operative position against endwise movement, means to control the movement of the rock shaft,

first, to a position to free the arms from the bearings, for removal thereof outward of the frames, and thereby enable the removal of the roller, second, rock the shaft to the position where said adjustment for alignment is made, 5 and third, to positions between two predetermined positions to instantly change for a heavy or light pressure of the roller, including a spring arm fixed to one end of the shaft, having an engagement with a cam faced lever pivoted to one 10 of said side frames, the arm provided with a spring controlled detent adapted to engage in perforations along a sector over which the arm swings, to lock the arm and connecting mechanism in any of the said adjusted positions. 15

24. A copying machine, comprising a drum adapted to hold a master, an impression roller co-acting with the drum, and a complete unit comprising a liquid container supporting mechanism for feeding copy sheets to the drum and delivering to the underside thereof a regulated uniform coating of the liquid from the container by means of an endless traveling belt, said container and mechanism being arranged and assembled for convenient unitary attachment to and removal from said machine without substantial disassembling of any other parts thereof. 20 25

26. A copying machine, comprising a drum and an impression roller co-acting therewith, and means adapted to moisten and feed the copy paper to said drum and impression roller, including a liquid container carrying a pair of feed rollers mounted above and free of the liquid, 30 and an endless traveling belt within the container, adapted to pick up liquid from the bottom thereof, to supply a quantity greater than required to said feeding means to moisten the copies, and means to adjust the quantity so delivered by a movable contact member, to a uniform distribution thereof and a separate means to instantly change the contact pressure between two predetermined and intermediate positions thereof, for a heavy or a light distribution. 35 40 45

26. In a copying machine, comprising a pair of feed rollers, rotatably carried at the top of a liquid container, one of which is supplied with liquid, at one side thereof, by a traveling endless belt adapted to pick up liquid from the bottom 50 of the container, to use the full supply therein, with an amount greater than the amount to be delivered over the roller to copy sheets passed between the rollers at another portion thereof, 55 means to regulate the amount so delivered to said copies, located between said delivery portion and said portion receiving the supply, including a contact member adapted to engage the roller under varying degrees of tension. 60
